TONGS

Filed March 31, 1928

William E. Root,
Inventor

Irving L. McCallum
Attorney

UNITED STATES PATENT OFFICE

WILLIAM E. ROOT, OF BLOOMFIELD, CONNECTICUT

TONGS

Application filed March 31, 1928. Serial No. 266,316.

This invention relates to the class of tools and pertains particularly to a pair of tongs designed especially for handling of wire of various degrees of circumference.

5 A primary object of the present invention is to provide in a manner as hereinafter set forth, a tong for the handling of wire wherein one of the jaw members may be adjusted to enable the user to obtain a firm grip on 10 the wire body over an area extending longitudinally thereof a distance equal to the length of the jaws.

A further object of the invention is to provide a tong of the above described character 15 wherein manipulation of a single member will enable the user to obtain the desired adjustment of the jaw for the purpose desired.

Other objects and advantages of the present invention will become apparent as the description of the same proceeds and the invention will be best understood from a detailed description of the accompanying drawing forming a part of the present invention, with the understanding, however, that the invention 25 is not confined to any strict conformity with the showing of the drawing but may be changed or modified so long as such changes or modifications mark no material departure from the salient features of the invention as expressed in the appended claim.

In the drawing:

Figure 1 shows the tong embodying the present invention, in side elevation.

Figure 2 is a sectional view taken substantially upon the line 2—2 of Figure 1.

Figure 3 is a sectional view taken substantially upon the line 3—3 of Figure 2.

Figure 4 is a section taken transversely of the shiftable element of one jaw, removed 40 from position.

Referring now to the drawing in detail wherein like numerals of reference indicate corresponding parts throughout the several views, the tongs comprises the handle members 1 and 2 which are arranged in crossed relation and secured in relative movable relation by the screw 3.

Each of the handle members 1 and 2 forwardly of the pivotal point is formed to provide a pair of elongated jaw members indi-

cated as a whole by the numerals 4 and 5. Each of the jaw members has an offset portion 6 adjacent the pivot point of the handles and the offset portions of the jaw 4 merges into a semi-circular portion 7 in which the concave side is directed toward the opposite jaw. This semi-circular jaw portion 7 is provided with a slot 8 which opens through the inner or concave face of the jaw and further has laterally opening slots 9 which extend from the slot or recess 8 through each side face thereof as clearly shown in Figures 1 and 3.

Associated with the semi-circular jaw portion 7 is a substantially semi-circular jaw plate 10, the curved edge of which is designed to fit snugly in the concave face of the jaw section while the straight edge portion 11 is tapered forming the V-shaped edge shown.

A laterally projecting flange 12 extends from each face of the member 10 and follows the curved edge thereof as shown in Figure 1, these flanges 12 bearing against the concave face of the jaw portion 7.

A bolt 13 extends radially through the body 10 and beyond the curved edge thereof terminating in the flat centrally apertured head or eye 14 which is designed to extend into the recess 8 to snugly fit therein.

A pivot securing pin 15 passes transversely through the jaw portion 7, through the slots 9, and through the eye or apertured head 14 of the pin or bolt 13. This pin 15 has a head 16 upon one end and threadedly receives upon the other end the nut 17.

The offset portion 6 of the jaw 5 merges into the straight V-shaped jaw portion 18, the groove of this jaw being directed toward the jaw portion 7 and being designed to receive the wedge shaped or tapered edge 11 of the shiftable jaw member 10.

From the foregoing it will be readily seen that when a wire or rod is arranged to extend longitudinally of the tong to position in the groove 19 of the jaw 18 the shiftable jaw member 10 can be so adjusted that the entire length of the tapered edge 11 will contact with the bar or wire thus giving a firm grip.

ping surface throughout the length of the opposed jaws.

While the foregoing description has been confined chiefly to reference to wires or circular pieces it is of course to be understood that these tongs may be effectively used upon flat pieces of work and by loosening the nut 17 upon the pin 15 the semi-circular jaw member can be rotated in the semi-circular portion 7 so that the work contacting edge 11 of the member 10 will fit through its length upon the work which rests upon the closed jaw member 18.

Having thus described my invention what I claim is:

A tong of the character described, comprising a pair of handles being in crossed relation, pivotal means between said handles, each of said handle members being extended 20 forwardly of the pivotal point and offset with respect thereto, one of said offset portions terminating in a straight jaw member, a curved jaw member extending from the other offset portion and having a groove in 25 the inner face thereof and laterally opening slots communicating with said groove, a jaw element having a curved edge designed to fit in said curved jaw member, a securing pin carried by said curved jaw member having 30 one end extended in said groove, a retaining pin extending transversely of the curved jaw member and engaging and holding the extended end of said pin, said straight jaw member being of substantially V-shaped 35 cross sectional design to receive said jaw element.

In testimony whereof I affix my signature.

WILLIAM E. ROOT.
